UNITED STATES PATENT OFFICE.

ERASTUS CORNING SOMERS, OF CORNING, NEW YORK; NELSON L. SOMERS
ADMINISTRATOR OF SAID ERASTUS CORNING SOMERS, DECEASED.

REVOLUBLE WINDOW.

SPECIFICATION forming part of Letters Patent No. 749,109, dated January 5, 1904.

Application filed September 3, 1901. Renewed November 18, 1903. Serial No. 181,737. (No model.)

To all whom it may concern:

Be it known that I, ERASTUS CORNING SOMERS, a citizen of the United States, and a resident of Corning, in the county of Steuben and State of New York, have invented a new and Improved Revoluble Window, of which the following is a full, clear, and exact description.

The invention relates to windows having sashes mounted to slide up and down and adapted to be turned on pivots for conveniently cleaning both sides of the window.

The object of the invention is to provide a new and improved window which is simple and durable in construction and arranged to permit of conveniently locking the sash to the slide to move the sash up and down or to unlock the sash from the slide for turning the sash on its pivots.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a sectional front elevation of the improvement, showing one side of the sash locked to the slide. Fig. 2 is a side elevation of the same, showing the sash in section and unlocked from the slide and turned into an angular position. Fig. 3 is a sectional side elevation of the same on the line 3-3 of Fig. 1. Fig. 4 is a side elevation of the mechanism for actuating the locking and unlocking bar, the parts being broken out. Fig. 5 is an enlarged sectional plan view of the improvement on the line 5-5 of Fig. 1. Fig. 6 is a sectional front elevation of the actuating mechanism for the locking and unlocking bar, the section being on the line 6-6 of Fig. 4. Fig. 7 is a similar view of the same on the line 7-7 of Fig. 4. Fig. 8 is a perspective view of one of the pivots for the sash. Fig. 9 is a like view of the removable head for the pivot. Fig. 10 is an enlarged sectional plan view of the improvement on the line 10-10 of Fig. 1, showing the sash locked to the slide, and Fig. 11 is a like view of the same with the parts

in a different position and showing the sash unlocked.

The window has a sash A provided on both sides, at or near the middle thereof, with pivots B, engaging bearings in a slide C, mounted to slide up and down in the usual guideways D, formed on the sides of the window-frame, as plainly indicated in the drawings. The pivot B is also engaged by the eye of a rod E, attached to one end of a counterbalancing chain or cord E', extending over the usual pulley E² and carrying at its other end a sash-weight. (Not shown.) Each side of the sash A is formed with a recess or groove A', extending nearly the length of the side, and into this recess is adapted to pass a bar F, preferably made of sheet metal and U-shaped in cross-section, as plainly shown in Figs. 5, 10, and 11. The sides of this bar F are formed with a number of angular slots F', engaged by pins F², extending transversely and attached to the slide C, so as to move the bar F. By moving the bar F upward it slides on the pins F², and as the slots F' are angular it is evident that the said bar F also slides sidewise and moves out of engagement with the recess A' on the sash A. (See Fig. 11.) When the bar F is moved downward, it slides sidewise in the opposite direction—that is, back into the recess A'—so that the sash A is held against turning on its pivot B. When the bar F is, however, in an uppermost position and out of engagement with the recess A', then the sash A is unlocked and can be readily turned on its pivots B for the purpose mentioned. The bar F is mounted to slide in a suitable guideway G, preferably made of sheet metal and secured to the slide C, as plainly indicated in Figs. 10 and 11. The middle portion of the bar F is formed with apertures F³, adapted to be engaged by hooks H, carried by the sides of the sash A, so as to hold the bar F against accidental sidewise movement after the bar is moved into position in the recess A'. The bar F is normally held in a lowermost position and in engagement with the recess A' by the action of a spring I, held on the guideway G and connected by a hook I' with a pin I² on the said bar F, as plainly indicated in Figs. 1 and 3. One of the apertures F³ is

adapted to be engaged by a lug J on the free end of a spring J', secured to the guideway G, so that when the bar F is moved into an uppermost position and out of engagement with the recess A' then the said lug J snaps into the aperture F³ to hold the bar F temporarily in an uppermost position—that is, during the time the sash A is turned on its pivots B slightly in either direction from a perpendicular line of slide C.

In order to move the bar F into an uppermost position, the following device is provided: Near the lower end of the bar F is arranged a link K, pivoted at K' to the bar and formed at its free end with an arm K², (see Figs. 4, 6, and 7,) extending through an opening F⁵ in one side of the bar F to a casing L, held on the slide C. This arm K² is adapted to be engaged by the angular portion N' of a lever N, fulcrumed at N² in the casing L and extending to the outside of the slide C, so as to be within convenient reach of the operator. When the lever N is swung upward, its angular portion N' imparts an upward movement to the arm K², so that the link K imparts an upward sliding motion to the bar F to move the same out of engagement with the side of the sash A. When the bar F moves upward, it places the spring I under tension, and at the same time the lug J of the spring J' engages one of the apertures F³ to hold the bar in an uppermost position. The lever N falls of its own gravity or the operator places it in lower positions immediately after raising it sufficient to allow lug J to engage the aperture F³ in bar F, which holds it until sash A is turned on its pivot B out of line with slide C; but the bar F still holds its upper position, being in contact with the sides of sash A until sash A is fully revolved or moved back to its perpendicular position in line with slide C, when the spring I pulls the bar F downward into the recess or groove in sash A, the apertures F³ in bar F engaging the hooks in the recess or grooves on the sides of sash A, thus automatically locking sash A to slide C.

The pivot B, above referred to, is preferably secured on a plate B', screwed or otherwise fastened to the sash A, and on the free end of the pivot B are formed lugs B², engaging corresponding recesses in a head B⁴, formed with a central aperture for the passage of a screw B⁵, screwing into the pivot B to hold the head B⁴ in place, and by adjusting the screw B⁵ with the pivot B the plate or head B⁴ presses the slide against the sash A to form a proper friction that will hold the sash A in any desired position after being turned upon the pivots B. (See Fig. 5.)

It is understood that when the sash A is locked by the bar F to the slide C the sash moves freely up and down with the slide to open and close the window, as desired, and when the sash is unlocked from the slide C, with the bar F then standing in an uppermost position, the sash A can be turned on its

pivots B to permit of conveniently cleaning both sides of the window from the inside of a room.

Having thus described my invention, I claim as new and desire to secure by Letters Patent—

1. A window having slides on which the sash is mounted to turn, and locking devices for locking the sash to said slides to move up and down with the latter, or to disengage the sash from the slide to allow the sash to turn on its pivots; each of the locking devices comprising a spring-pressed bar slidable up and down and sidewise on the said slide to move it out of and into a recess or groove in the said sash, and adapted to be automatically moved into the recess or groove of the sash when the sash is moved into a vertical position, as set forth. 85

2. A window having slides on which the sash is mounted to turn, a bar slidable up and down and sidewise so as to move in and out of a recess or groove in the sash, means for moving the bar upward to move it out of the recess or groove of the sash, and means for locking said bar raised, said means being automatically released when the sash is moved into a vertical position, as set forth.

3. A window having slides on which the sash is mounted to turn, locking devices for locking the sash to said slides to move up and down with the latter, or to disengage the sash from the slide to allow the sash to turn on its pivots, each of the locking devices comprising a spring-pressed bar slidable up and down and sidewise on the said slide to move it out of and into a recess or groove in the said sash; the said bar having angular slots, pins carried by the slide and extending through the said angular slots, means for moving the bar upward, and means for locking the bar raised, as set forth.

4. A window having slides on which the sash is mounted to turn, locking devices for locking the sash to said slides to move up and down with the latter, or to disengage the sash from the slide to allow the sash to turn on its pivots, each of the said locking devices comprising a bar slidable up and down and sidewise on the said slide to move it out of and into a recess or groove in the said sash; the said bar having apertures, and hooks on the side of the sash to engage the said apertures at the time the bar slides downward into engagement with the said recess, as set forth. 115

5. A window having slides on which the sash is mounted to turn, locking devices for locking the sash to said slides to move up and down with the latter, or to disengage the sash from the slide to allow the sash to turn on its pivots, each of the locking devices comprising a bar slidable up and down and sidewise on the said slide to move it out of and into a recess or groove in the said sash; and manually-controlled means for moving the bar up and down, the said means comprising a link pivotally connected with the said bar, the link having an arm at its free end, a lever under

- the control of the operator and having an angular portion for engaging the said link-arm, and a spring pressing the said bar, as set forth.
- 5 6. A window having slides on which the sash is mounted to turn, locking devices for locking the sash to said slides to move up and down with the latter, or to disengage the sash from the slide to allow the sash to turn on its pivots, each of the locking devices comprising a bar slideable up and down and sidewise on the said slide to move it out of and into a recess or groove in the said sash, manually-controlled means for moving the bar up and down, the said means comprising a link pivotally connected with the said bar, the link having an arm at its free end, a lever under the control of the operator and having an angular portion for engaging the said link-arm, a spring pressing the said bar, and a second spring having a lug for engaging an aperture in the said bar, as set forth.
- 10 7. A window having recesses in its sides and hooks extending in the said recesses, slides on which the sash is mounted to turn and bars carried by the slides and adapted to move into the said recesses, the bar having apertures for engaging the said hooks as set forth.
- 15 8. In a window, the combination with a grooved sash, and a slide to which the sash is pivoted, of a sliding and spring-pressed bar movable in and out of the groove of the sash, means for moving the bar upward, against the action of its spring and a locking device 35 for locking the bar raised until the sash is turned out of line with the slide, as set forth.
- 10 9. In a window, the combination with a grooved sash, and a slide to which the sash is pivoted, of a sliding bar movable in and out of the groove of the sash, a spring connected with the bar for holding it in a lowermost position, means for raising the bar against the action of the spring, and a spring-catch for engaging the bar to hold it until the sash is 40 turned out of line with the slide, as set forth.
- 15 10. In a window, the combination with a grooved sash having hooks in said groove, and a slide to which the sash is pivoted, the slide being provided with a guideway, of a 45 **U**-shaped bar having guided movement in the guideway of the slide and movable in and out of the groove of the sash, the bar being provided in its connecting member with openings to receive the hooks of the sash, a spring 50 connected with the bar to hold it in a lowermost position, means for raising the bar against the action of its spring, and means for locking the bar raised until the sash is turned out of line, with the slide, as set forth.
- 20 25 30 In testimony whereof I have signed my name to this specification in the presence of two witnesses.
